PATTERN PRESSER.

Emil Herbert Wirth, Hartmannsdorf, near Chemnitz, Germany, assignor to the Firma Emil Wirth Wirkmaschinenfabrik, Hartmannsdorf, near Chemnitz, Germany

Application May 18, 1938, Serial No. 208,696
In Germany July 8, 1937

1 Claim. (Cl. 66—98)

The present invention relates to pattern pressers such as are used in connection with warp knitting machines.

Pattern pressers as heretofore known consist of a presser bar provided with teeth arranged in accordance with the pattern to be produced, said teeth serving the purpose of pressing the needles required for the production of the desired patterns. For each pattern to be produced, therefore, a special pattern bar is required.

According to the present invention the pattern presser consists of a presser bar provided with exchangeable presser teeth which may be mounted upon the presser bar according to the pattern to be produced. To obtain an easier handling of the presser teeth, each of them preferably is of such a width, that at least two needles may be operated by the same. To render the presser teeth useable for any pattern, the teeth may be so constructed that they have a presser edge at one side only, so that individual needles also may be pressed.

It is an object of the present invention to provide a pattern presser having the presser teeth thereof capable of being rearranged thereon as desired, in order to present said teeth in various positions, as required for the production of different patterns.

Some constructions of pattern pressers according to the invention are shown by way of example in the accompanying drawings.

In these drawings:

Fig. 1 is a plan view of a pattern presser according to the invention.

Figs. 2 and 3 show cross sections through the pattern presser with presser teeth inserted in different positions.

Figs. 4—9 show three different forms of presser teeth each in elevation and in plan view, and

Fig. 10 illustrates a combination of presser teeth of different form in a width for two needles.

Figure 11 is a side detail view of a pattern presser, according to the present invention, mounted upon a warp knitting machine.

Referring now more particularly to the accompanying drawings wherein like and corresponding parts are designated by similar reference characters, numeral 1a indicates a presser bar having formed longitudinally thereof three notches or grooves 2a, 3a and 4a. Numeral 5 refers to a plurality of presser teeth, each of which is provided upon the lower face thereof with projections 6, 7 and 8 which are sized and positioned to fit within any of said grooves 2a, 3a and 4a and which teeth are further provided

upon an upper face thereof with a presser edge 9. Those of the presser teeth 5 which are required to be in an operative position, that is, in a position for pressing against needles of a warp knitting machine, are positioned upon presser bar 1a with projections 7 and 8 inserted within grooves 2a and 3a respectively, whereas, the presser teeth 5 which are to remain in an inoperative or non-contacting position have the projections 6, 7 and 8 positioned within the grooves 2a, 3a and 4a respectively. The first of said tooth positions is disclosed in Figure 2 of the drawings, whereas, the second mentioned position is shown in Figure 3. With the teeth 5 thus mounted upon presser bar 1a, a plate 10 is mounted upon the upper face of the teeth in both of said positions and a bolt 11 passing through an opening thereof and being in threaded engagement with a corresponding opening in bar 1a, is caused to be tightened for retaining said teeth 5 between the plate 10 and presser bar 1a.

The presser teeth are of a width sufficient to press two needles with the presser edge 9 thereof when mounted in the aforementioned operative position. As shown in Figure 1 of the drawings, the teeth 5 in the operative position are spaced from one another by the teeth 5 in the inoperative position, with the result that alternating pairs of needles are pressed by the presser teeth in the said operative positions. Such a double width tooth is shown in Figures 4 and 5 of the drawings.

A modified form of presser tooth 5a is shown in Figures 6 and 7 with a second modified form in Figures 8 and 9. The first modified form has the usual projections 6, 7 and 8 upon the lower face thereof with a body being of a width substantially equal to the body of the presser tooth disclosed in Figures 4 and 5, but having the portions thereof forming the presser edge 9a of a width approximately one-half the width of the body. Such a modified form of presser tooth may be positioned upon presser bar 1 next to a presser tooth as shown in Figures 4 and 5 and thereby fill in a space substantially equal to the space filled by the principal form of tooth and yet, at the same time, present a presser edge 9a which will press a single needle.

The second modification shown in Figures 8 and 9 is similar to that of the first mentioned modified form but, as best shown in Figure 9, has a presser edge 9b of a single needle width but formed contiguous with and extending from a side of the tooth 5b opposite to the side thereof

upon which the presser edge 9a of said first form extends contiguously.

By mounting the presser teeth 5, 5a and 5b of the various modifications hereinabove described upon a presser bar 1a, an arrangement, as for example as shown in Figure 10, can be obtained. That is, four needles may be pressed, then one needle, two needles, one needle and three needles with respective spaces for causing one needle, then two needles, three needles and four needles to remain inoperative. The presser teeth 5a, 5b as shown in Figures 6 to 9 inclusive, will each press one needle and leave a needle therebeside inoperative or if the two modified forms of the needles are placed side by side, each will press a needle and leave a pair of needles between the pressed needles inoperative. As a result thereof, the presser teeth may be positioned in any desired arrangement, depending entirely upon the pattern to be formed. After the presser teeth 5, 5a and 5b are mounted upon the presser bar 1a as desired, plate 10 and bolt 11 are positioned thereon for retaining the presser teeth in their given position.

Presser teeth may also be made of a width suitable for acting upon more than two needles at a time and such presser teeth may be provided with a presser edge in a manner as shown in Figures 6 and 7 or 8 and 9 respectively, so that, for example, one needle or a plurality of needles may be pressed, depending upon the width and the shape of the presser edge of the presser tooth.

The numerals upon the drawings having no lead lines therefrom indicate the number of needles to be pressed or to remain inoperative, depending upon the width and position of the presser tooth therebeside.

Pattern pressers as hereinabove described, as best shown in Figure 11 of the drawings, are connected to a link 20 of a warp knitting machine and are slidably arranged upon a flat portion of a plain presser 13. Said plain presser 13 is

mounted upon a bearing 12 and adapted to be moved to and from the bearded needles 14. Bearing 12 is fixed upon a holder 15 which is reciprocated by a cam shaft of the warp knitting machine to effect the above mentioned movements of the presser 13. The plain presser 13 is, by means of an intermediate link 16, connected to an eye 17 which is provided on a joint member fixed upon a shaft 18 journaled in the holder 15. Due to this construction, the plain presser may be reciprocated upon the bearing 12, as indicated hereinbefore. Approximately diametrically opposite the eye 17 is a second eye 19 fixed to said joint member and said second eye 19 is, by means of said intermediate link 20, connected to the presser bar 1a of the pattern presser according to the present invention. Fixed upon the shaft 18 is a fork 21 carrying at the end of each prong a roller 22 and 23 respectively cooperating with a double cone shiftably mounted upon a shaft 25 to alternately bring the two pressers 13 and 1a into their operative position. In this manner, presser teeth, which are mounted in said operative position, contact the bearded needles 14, whereas, the presser teeth, in the inoperative position, remain out of contact at all times with said needles and by changing the arrangement of the presser teeth, various of the bearded needles 14 will be obviously contacted, thereby forming various patterns as desired.

What I claim is:

A pattern presser for use upon warp knitting machines comprising a presser bar provided with a plurality of grooves, presser teeth each of a width sufficient to press a plurality of needles at a time being detachably carried by said presser bar and said presser teeth each having projections corresponding to said grooves carried thereby in order that said presser teeth may be mounted upon said presser bar in various positions thereof.

EMIL HERBERT WIRTH.
